United States Patent

Des. 238,195
Patented Dec. 23, 1975

238,195

TOY VEHICLE

Howard J. Morrison, Deerfield, Ill., assignor to
Marvin Glass & Associates, Chicago, Ill.

Filed Jan. 23, 1974, Ser. No. 435,639

Term of patent 14 years

Int. Cl. D21—01
U.S. Cl. D34—15 AJ

Fig 3

Fig 4

FIG. 1 is a top plan view of a toy vehicle showing my new design;

FIG. 2 is a side elevational view thereof, the side opposite being substantially identical;

FIG. 3 is a front elevational view thereof;

FIG. 4 is a rear elevational view thereof; and

FIG. 5 is a bottom plan view thereof.

I claim:

The ornamental design for a toy vehicle, as shown and described.
